UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT ROTATION OF BOBBINS.

Application filed October 13, 1924. Serial No. 743,204.

This invention relates to improvements in automatic weft replenishing looms and more particularly to looms of the type having bobbins of different colors arranged in 5 groups to be delivered to any one of several shuttles.

In looms of this type it is common to arrange the bobbins in vertical compartments from the lower ends of which the 10 bobbins are discharged to a common transier point. It has been found that as the bobbins await transfer they are subject to such vibrations as cause them to rotate on their axes. The result of this is either to wind up 15 the end which extends to the thread holder or to unwind an excess of filling such as will become entangled with some part of the loom. In either event the filling is likely to be broken or improperly threaded at the 20 time of transfer and it is the general object of my invention to provide improved means for arresting rotation of the bobbins.

The device shown in application Serial 25 No. 690,268 employs a weight for each compartment so arranged that it may be raised and held temporarily away from the bobbins while the operator is placing a fresh supply 30 of bobbins in the compartment. A plunger is arranged to pass under an overhanging portion of each weight and is withdrawn 35 at each actuation of the replenishing mechanism to advance a bobbin to transfer position. With this construction the weights cannot be released by a downward pressure on the weights themselves.

It is a more particular object of my invention to provide a plurality of yielding means for holding the weights releasably, all of said means being controlled from a 40 single point and the weights being releasable by hand independent of the replenishing mechanism.

It is a further object of my invention to 45 provide means for controlling all of the weight holding means from a common point so that the operator may release the weights by a single motion.

With these and other objects in view 50 which will appear as the description proceeds my invention resides in the combination and arrangement of parts hereinafter described and set forth in the claims.

In the accompanying drawings, wherein I have shown one form of my invention,

Fig. 1 is a side elevation of a replenishing mechanism having my invention applied thereto as viewed from the interior of the loom, 55

Fig. 2 is a top plan view of certain of the 60 structure shown in Fig. 1,

Fig. 3 is a front elevation looking in the direction of arrow 3, Fig. 1,

Fig. 4 is a fragmentary rear elevation of the structure shown in Fig. 1, and

Fig. 5 is a detail perspective view of one 65 of the weights.

Referring to the drawings it will be seen that I have provided a weft replenishing mechanism 10 having mounted thereon for sliding and angular movement a shaft 11 to 70 which are secured fingers 12. Upright slides 13, one for each compartment, are controlled one at a time by the fingers and are provided at the upper ends thereof with spring actuated dogs 14 which cooperate with an elongated lever 15 secured to shaft 16. The shaft 16 is journaled in the frame of the replenishing mechanism and is oscillated by the lever 15 when the latter is depressed to raise the transierer latch (not shown) into 75 engaging position with the bunter on the lay. Extending from the frame 10 are flanges 17 which define bobbin compartments 18. The matter thus far described is 80 set forth in Patent No. 1,030,748.

In carrying out my invention I provide the upper end of the frame 10 with extensions 30 and 31, respectively. Extending 85 across the top of the flanges 17 is a slide 32 provided with longitudinal slots 33 which receive guide studs 34 threaded into the upper portion of the frame 10. The slide 32 is provided with a plurality of transverse slots 35 which register with the compartments 18. Extending through each of the slots 35 is a spring weight holder 36 having a horizontally extending portion 37 by which it may be adjustably secured to the slide by means of screw 38. Each spring 90 holder 36 has a downwardly extending end 39 provided with an offset 40 which terminates in a downwardly and rearwardly inclined tip 41. The rear end of slide 32 is 95 bent downwardly and has threaded therein a stop screw 42 positioned for engagement with the extension 30 and the forward end 100 of the slide is provided with a downwardly 105 inclined tip 43.

extending arm 43 positioned for engagement with a coiled compression spring 44 received in a pocket 45 formed in the forward extension 31.

6 The devices for engaging the bobbins and preventing rotation thereof comprise a series of weights 46 each having a suitable hand hold 47 and fin 48. The upper end of each weight is provided with a depression 49 into 10 which extends a rounded overhang 50 projecting somewhat beyond and above the inner lower wall of the depression. The overhang 50 is proportioned to lie above the offset 40 in the spring 36 when the weight is 15 raised out of the operator's way. Guide strips 51 are secured to the frame 10 and spaced from certain of the flanges 17 to define grooves for the fins 48.

From the matter thus far described it is 20 to be understood that the weights 46 are normally in the compartments, being held therein by the engagement of the fins 48 with guide strips 51, and rest on the top bobbins to prevent their rotation. When it is 25 desired to place full bobbins in the compartments 18 as the latter are depleted by the action of the replenishing mechanism, the operator will lift the weights as by the handle 47 until the offset 40 of the corresponding 30 spring passes under the overhang 50. This will be done for as many compartments as need replenishing, the weights being held in elevated position so as not to interfere with the operator. When all the compartments 35 have been filled the operator can press the depending arm 43 rearwardly against the action of spring 44, the result of which will be to move all of the depending springs 36 away from the weights so that the latter will 40 fall on the bobbins. It is to be understood that spring 44 is sufficiently strong to withstand the combined opposed pressure of all the springs 36.

It is found in devices of this kind that the 45 operator will occasionally leave the loom with the weights in raised position and in order to insure releasing of the weights I have provided the slide with an offset boss 52 which is rounded as shown in Fig. 1 and 50 positioned for engagement with the upper arm 53 of a lever 54 pivoted as at 55 to the frame 10. The lower arm 56 of lever 54 is provided with a cam face 57 which is positioned for engagement with the inner end 58 of a lever 59 secured to shaft 16 in adjusted position by means of set screw 60. These parts are so proportioned that a downward movement of the lever 59 caused by a 55 partial rotation of shaft 16 will pass end 60 58 thereof across the cam 57 to rock the lever 54 on its pivot and cause the slide 32 to move against the action of spring 44.

In the normal operation of the device the 65 slides 13 will be down and at indication of substantial weft exhaustion the slide corre-

sponding to the depleted shuttle will be raised by means of one or another of the fingers 12, the latter being positioned by a connection with the box motion. As the slide 13 assumes its upper position the dog 14 pivoted thereon will swing outwardly to the position shown in Fig. 3 and will overhang the lever 15. When the indicating shuttle again returns the slide 13 will be lowered by the finger 12 which previously raised it 75 and the dog 14 will engage lever 15 and cause a partial rotation of shaft 16, the result of which is to move the slide 32 as previously described. Thus it will be seen that the mechanism is given a weight-releasing movement at each operation of the replenishing mechanism.

From the foregoing it will be seen that I have provided a series of devices to retain and release bobbin engaging weights, all of said devices being controlled from a common point and that the weights can be released independently of any action of the parts of the replenishing mechanism. Also, the weights are so constructed that if desired the operator can immediately release each weight after filling the corresponding compartment because of the yielding action of the holding springs 36.

Having thus described my invention it will be apparent that changes and modifications may be made therein by those skilled in the art without departing from the spirit and scope of the invention, and I do not wish to be limited to the details herein disclosed, but what I claim is:

1. In a weft replenishing mechanism for looms, a plurality of bobbin compartments, a weight movable in each compartment, means for holding said weights yieldingly in raised position and means common to said means to release said weights simultaneously.

2. In a weft replenishing mechanism for looms, a plurality of bobbin compartments, a weight associated with and movable in each compartment for engagement with the bobbins therein, a series of weight retaining means, one for each weight, to hold any or all of said weights in raised position, and a single device common to all of said retaining means to move the latter to weight releasing position.

3. In a weft replenishing mechanism for looms, a plurality of bobbin compartments, a weight for each compartment for engaging the bobbins therein, a slide common to all the compartments, resilient means extending from the slide into each compartment and positioned for engagement with the weights to hold the latter in raised position, and means to move said slide to release all of said weights.

4. In a weft replenishing mechanism for looms, a plurality of bobbin compartments,

a bobbin engaging weight in each compartment, a slide common to all the compartments, and means carried by the slide to retain the weights, sliding movement of the 5 slide acting to release the weights.

5. In a weft replenishing mechanism for looms, a plurality of bobbin compartments, a bobbin engaging weight in each compartment, a resilient weight engaging device in 10 each compartment and means to cause said devices to move in unison to release the weights.

6. In a weft replenishing mechanism for looms, a plurality of bobbin compartments, 15 a weight associated with each compartment to engage the bobbins therein, a plurality of devices, one in each compartment, to engage the weights, means acting to hold said devices in weight retaining position, and means 20 to move said devices in unison to weight releasing position.

7. In a weft replenishing mechanism for looms, a plurality of bobbin compartments, bobbin engaging weights movable in the 25 compartments, a yielding retaining device for each weight, resilient means strong enough to overpower all of said retaining weights and hold the same in weight retaining position, and means to move said retaining 30 devices in unison against the action of the resilient means.

8. In a weft replenishing mechanism for looms, a plurality of bobbin compartments,

a weight for each compartment, yielding retaining means for each weight, each of said 35 means being capable of slight yielding movement independently of the remaining means by downward pressure on the associated weight to release the latter.

9. A weight releasing slide for a weft replenishing mechanism having a plurality of compartments and weights movable in the compartments, said slide having a plurality of weight retainers extending therefrom and having means formed thereon by which said 45 slide can be actuated to move all of said retainers in unison.

10. A weight releasing slide for a weft replenishing mechanism having a plurality of compartments with weights therein, said 50 slide having a plurality of perforations therein through which extend weight retainers, and means formed on the slide by which the latter may be actuated to move 55 all of said retainers in unison.

11. A weight retaining slide for weft replenishing mechanism for looms having compartments with weights therein, said slide having a plurality of resilient weight retainers secured thereto and extending therefrom and means formed on the slide by which the latter may be actuated to move 60 all of the weight retainers in unison.

In testimony whereof I hereunto affixed my signature.

RICHARD GREENLEAF TURNER.
